UNITED STATES PATENT OFFICE.

HORACE GEORGE CRITTENDEN, OF JOSLIN, SOUTH AUSTRALIA, AUSTRALIA.

OPERATING MECHANISM FOR THE COMMUTATORS OF AUTOMOBILE ENGINES.

Application filed July 28, 1921. Serial No. 488,255.

To all whom it may concern:

Be it known that I, HORACE GEORGE CRITTENDEN, a subject of the King of Great Britain, residing at Joslin, in the State of 5 South Australia, Commonwealth of Australia, have invented certain new and useful Improvements in Operating Mechanism for the Commutators of Automobile Engines, of which the following is a specification.

10 This invention relates to improved operating mechanism for the commutator of automobile engines, and particularly of those automobile engines in which the commutator is ordinarily supported in a position where 15 oil from the surrounding parts may interfere with its working or reduce its efficiency.

The object of this invention is to provide means whereby a commutator can be mounted and operated conveniently in a position 20 which will be readily accessible and at the same time less liable to be influenced by waste oil than is the case with appliances at present usually employed.

Another important object of my invention 25 is to enable the necessary elements which I have invented to be fitted on to the existing engine without requiring any serious alteration to the structure.

My invention is particularly applicable to 30 a type of engine which is generally known as a Ford type of motor.

In this type of engine a driven toothed wheel is mounted on the cam shaft and is surrounded and protected by a metal casting. 35 For the purpose of my invention I cut a hole or opening in the outer side or top of this protective casting adjacent to the periphery of the toothed wheel, such opening being of sufficient size to enable the teeth of a similar additional wheel to be admitted 40 and to mesh with the teeth of the wheel first above referred to.

The additional wheel is supported on a spindle which has bearings on a supplemental 45 casing which is rigidly attached by suitable means to the existing casting and also to the bed of the engine. The spindle of the toothed wheel operates a timer the casing of which is likewise adjustably supported on 50 the supplemental casing.

My invention is also applicable to engines 55 wherein the wheel of the self starting device is geared into the cam shaft wheel. In such an arrangement my supplemental casing is similarly mounted onto the extended casting which carries the self starter wheel, such ex-

tended casting being cut or constructed with an opening to allow the wheels of the added part to gear into and mesh with the wheels of the self starter substantially in the manner described with regard to the previous example.

But in order that my invention may be clearly understood I will now describe the same by aid of the accompanying illustrative drawings wherein:

Fig. 1 is an end view of my invention as applied to the Ford type of engine showing the ordinary casting surrounding the cam shaft and my casing attached thereto.

Fig. 2 is a sectional view of the adjacent casings illustrating gearing contained therein.

Fig. 3 is a sectional side view of Fig. 1 showing an ordinary distributor of known type attached to the spindle of the driven wheel contained in the supplemental casing.

Fig. 4 is a plan of Fig. 3 showing means for attaching the supplemental casing to the existing casting.

Fig. 5 is a modification of the preceding figures showing the application of my supplemental casing when the position otherwise used is occupied by the intermediate mechanism of self starting gear.

In each of the illustrations similar letters of reference are used to denote similar or corresponding parts wherever they occur.

In the drawings *a* is a portion of the cylinder block showing the position of the cam shaft *b* within the existing casting *c* upon which an ordinary driven toothed wheel *d* is mounted as at present in use.

In a convenient position in the existing casting and adjacent to the outer periphery of the toothed wheel *d* I cut a hole or opening *e* of sufficient width to allow a similar toothed wheel to mesh with the teeth of the existing wheel and I supply a supplemental casing *f* having a supporting boss *g* cast therein so as to constitute a bearing for the spindle *h* of a driven toothed wheel *j* of similar diameter and equal number of teeth to the wheel *d* as illustrated. The construction of the bearing for the spindle may be modified in such a manner as may be desirable. On the side of my supplemental casing which is adjacent to the cylinder block I form an extended drum *k* which serves as a support for the timer casing *l*, the distributor chamber being indicated at *m* having a receiving terminal *n* and four dis-

tributing terminals *o* arranged thereon, the central terminal being provided for the accommodation of the receiving wire in the magneto and the distributing terminals being used for the attachment of the wires which convey the electric current for sparking purposes to the four cylinders of the engine. The spindle *h* passes into or is otherwise connected with a rotating contact arm 10 or other device of known structure contained in the distributor *m* which rotates in unison with the spindle *h*. The timer casing is capable of a slight rotation for timing or adjustment purposes, and when set 15 in the correct position is retained by any convenient means such for instance as the slot and screw device shown at *p* and *q*. For the purpose of more firmly securing my supplemental casing in position I form 20 the base portion *f'* thereof to a radius corresponding with the external radius of the existing casting *c* and I construct a lug *f''* which overlaps the outer portion of the existing casting and abuts upon a corresponding 25 lug *c'* on the existing casting, the said lugs being securely drawn together and held by a bolt and nut or other fastening device such as *f'''*. As an additional means for fixing the supplemental casing I construct a lug *f''''* near the base of the casing 30 which rests upon the cylinder head and is secured thereto by an existing bolt *a'*. This arrangement when properly fitted holds the supplemental casing to the casting and enables the driven toothed wheel *j* to mesh with 35 the wheel *d* when the former is mounted upon its spindle. A short lug *r* is provided upon the timer casing *l* to render the latter capable of adjustment for advancement or 40 retardation of the sparking mechanism by aid of any suitable connecting lever.

Any engines in which the self starting gear is provided and occupies the position which I desire to use for my distributing 45 mechanism as above described I extend my supplemental casing beyond the casting which is used for the accommodation of the self starting gear. Such arrangement is shown in Fig. 5 where the frame of the self starting mechanism is indicated at *s* and its toothed wheel *t* is indicated by the dotted line encased in an extension *c''* of the existing casting. In this arrangement and for

the purposes of my invention I likewise cut an opening in the extension *c''* adjacent to 55 the periphery of the teeth of a self starter and I mount my supplemental casing thereon by any convenient means such for instance as the bolts or studs *u*, the supplemental casing in this instance as in the 60 previous case having its base or contact portion constructed in such a manner that it sits firmly upon the extension of the original casting and can thus be held with sufficient rigidity to support the spindle of my toothed wheel *j* in its proper bearings, said toothed wheel being of similar diameter and corresponding in its number of teeth with the toothed wheel *d*, the toothed wheel *t* of the self starter in this instance merely acting as an intermediate bridge wheel which gives rotation as desired, but as under this arrangement the rotation of the wheel *j* will be in the reverse direction to that of the 65 previous figures, the wires from the distributor will require to be correspondingly reversely adjusted. A low tension wire is provided at *v*.

What I claim is:—

In operating mechanism for the commutator of an automobile engine, the combination with a self starting device having a toothed wheel in mesh with a toothed wheel 80 on the cam shaft and an opening cut in the extended portion of a casting which is adapted to enclose the wheel and the said self starting arrangement, of a supplemental casing mounted on the said casting so as to 85 embrace the walls of the said opening in the casting, a spindle rotatably journaled at one end in said supplemental casing and having its opposite end projecting through a flanged 90 opening in the casing, a toothed wheel carried by the spindle and disposed in said casing and adapted to mesh with the first named 95 toothed wheel of the starting device, and a timer casing having an open end adapted to embrace the flange inscribing the opening in the supplemental casing, the said spindle being adapted to project into the 100 timer casing to rotate the mechanism enclosed therein.

In testimony whereof I affix my signature.
HORACE GEORGE CRITTENDEN.

Witness:

JOHN HERBERT COOKE.
